ATTORNEYS.

UNITED STATES PATENT OFFICE.

DAVID TEETS, OF NEW YORK, N. Y.

CHIMNEY-COWL.

SPECIFICATION forming part of Letters Patent No. 397,669, dated February 12, 1889.

Application filed April 13, 1888. Renewed December 14, 1888. Serial No. 293,659. (No model.)

To all whom it may concern:

Be it known that I, DAVID TEETS, of the city, county, and State of New York, have invented a new and Improved Chimney-Cowl, of which the following is a full, clear, and exact description.

My invention relates to an improvement in chimney or ventilator cowls, and has for its object to provide for the free discharge of the products of combustion at all times and to obviate the objectionable downdraft.

The invention consists in the construction and combination of the several parts, as will be hereinafter fully set forth, and pointed out in the claims.

Reference is to be had to the accompanying drawings, forming a part of this specification, in which similar figures of reference indicate corresponding parts in both the views.

Figure 1 is a side elevation, partly in section; and Fig. 2 is a bottom plan view.

In carrying out the invention the body 10, which is preferably cylindrical in contour and adapted for contact with the chimney through the medium of a base piece or plate, is connected with an upper annular section or ring, 11, by means of a series of equidistant vertical strips, 12, which strips are essentially U-shaped in cross-section, as shown in Fig. 2. The strips 12 are attached so that their edges turn outward from the body-sections 10 and 11, and are secured to both of the aforesaid by means of rivets 13, solder, or in any other approved or suitable manner. By this construction the body is provided with a series of longitudinal peripheral slots.

In completing the body of the ventilator a series of semi-cylindrical conductors, 14, are employed, whose side edges are turned outward, thus forming flanges 15, as best shown in Fig. 2. These conductors are adapted to cover the spaces intervening the U-shaped connecting-plates; and to that end the flanges 15 of the conductors rest on the side edges of the plates 12, and are preferably united thereto by a series of rivets, 16, as best illustrated in Fig. 2. The rivets 16 are usually placed one at each end of the conductors and one in the center, the end rivets passing, respectively, through the lower cylindrical body, 10, and through the upper section, 11, whereby all

the parts are securely and rigidly united. By attaching the conductors 14 in this manner their cylindrical surfaces are upon the outer side of the ventilator and form a series 55 of passages leading from the lower section, 10, upward in the direction of and beneath a cap, 17, which cap is attached to the body-section 11 by suitable brackets, 18. The cap 17 is preferably conical in shape, and so attached 60 to the section 11 that a space, 19, will intervene the upper surface of the cap and the upper edge of the said section. The cap 17 is also made of such a diameter that the outer edges will project beyond and over the conductors 14.

Thus in operation, should the downdraft be severe, the smoke will find unobstructed exit through the several conductors downward and be effectually prevented from returning to the flue, a portion of the smoke also finding its way out between the section 11 and the cap. Ordinarily, should an updraft occur, the conductors facilitate the exit of the smoke from the body of the ventilator by forming a section immediately below the cap.

By reference to the drawings in the above description it will be readily seen that the construction of the ventilator is not only simple, but economical and durable.

Having thus described my invention, I claim as new and desire to secure by Letters Patent—
1. In a chimney-cowl, the combination, with a series of vertical equidistant strips separated by slots, of a series of semi-cylindrical plates arranged vertically, covering said slots, and serving as smoke-conductors, as shown and described.

2. In a chimney-cowl, the combination, with the lower cylinder, 12, the upper ring, 11, and the equidistant essentially U-shaped plates 15, which connect them, of a series of semi-cylindrical conductors attached to the connecting-plates and spanning the space intervening said plates, and a cap attached to but 95 separated from the upper ring, substantially as and for the purpose specified.

DAVID TEETS.
